CLAIM

The ornamental design for a panda bubble toy, as shown and described.

DESCRIPTION

FIG. 1 is a front view of a panda bubble toy in accordance with the present invention.

FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines show portions of the panda bubble toy that form no part of the claimed design.
